UNITED STATES PATENT OFFICE

2,063,642

ELECTRIC HEATING UNIT

Peter H. Vanden Berg, Ontario, Calif., assignor
to Edison General Electric Appliance Company,
Incorporated, Chicago, Ill., a corporation
of New York

Application September 7, 1933, Serial No. 688,470

3 Claims. (CL 201—67)

This invention relates to electric heating units, and has for its object the provision of an improved and inexpensive device of this character and method of making it.

5 While not limited thereto, this invention has particular application to electric heating units of the sheathed wire type wherein a resistance conductor is embedded in a compacted mass of powdered insulating material enclosed by a metallic sheath, such as described and claimed in the 10 United States patent to C. C. Abbott, No. 1,367,341, dated February 1, 1921.

One object of this invention is the provision of 15 an improved terminal arrangement for electric heating units of this type.

In accordance with this invention, a resistance heating element is mounted lengthwise within a metallic tubular member. This tubular member in turn is mounted lengthwise within another metallic sheath of somewhat larger diameter. One 20 end of the resistance element is electrically connected with a terminal, which is mounted within and which projects from the tubular member, while its other end is electrically connected with the tubular member. The tubular member thus 25 constitutes a terminal for conducting current to one end of the resistance element. By reason of the foregoing arrangement, external electrical connections can be made at one end of the heater. 30 These connections, however, may be made at both ends, if this arrangement is preferred.

The resistance element is electrically insulated throughout its length from the tubular member that surrounds it and this member is electrically 35 insulated throughout its length from the outer enclosing sheath.

For a more complete understanding of this invention, reference should be had to the accompanying drawing, in which Fig. 1 is an elevation 40 in section of an electric heating unit arranged in accordance with this invention at one stage of its construction; Fig. 2 is a sectional view taken through the lines 2—2 of Fig. 1; Fig. 3 is an elevation of the heating unit shown in Fig. 1, but at 45 a more advanced stage in its construction, portions being broken away so as to illustrate certain structural details; and Fig. 4 is a finished heating unit arranged in accordance with this invention, parts being broken away so as to illustrate certain details of construction.

50 Referring to the drawing, in one form of this invention, a sinuous or helical resistance element 10 is mounted within and centrally of a metallic tubular member 11. As shown, the resistance element 10 extends lengthwise of the tubular mem-

ber 11 and is electrically connected at one end, its right-hand end, as viewed in the figures, to a terminal member 12 which is arranged centrally of the tubular member 11, but which projects from its end, as clearly shown in Fig. 4. The other 5 end of the resistance element is electrically connected with the corresponding end of the tubular member 11 by means of a screw member 13 and a washer 14. This screw 13, as shown, is passed through an aperture 15 provided for it substantially in the center of the washer. The washer 14, therefore, is in mechanical and electrical engagement both with the tube 11 and with the screw member 13 to which the resistance element 10 is directly connected.

15 The tubular member 11 is enclosed by an outer metallic sheath 16 of somewhat larger diameter and is in concentric relation with it.

The resistance element 10 is embedded in a compacted mass of powdered heat refractory 20 electrically insulating material 17, such as magnesium oxide. The tubular member 11 is electrically insulated throughout its length from the enclosing sheath 16 by an electrically insulating layer 18 formed of a similar insulating material. 25

In the finished heater, as shown in Fig. 4, the two ends of the tubular member 11 project from the associated ends of the enclosing casing 16, and the terminal member 12 projects from the 30 associated end of the tubular member 11.

35 By reason of the foregoing arrangement, it will be observed that the tubular member 11 constitutes a terminal for one end of the resistance element completely surrounding the element and also the terminal 12 connected to the other end 35 of the element. This arrangement possesses the advantage that the external electrical connections may be made at the same end of the heating unit. This, of course, is desirable when the unit is to be inserted in an opening in the body 40 or article to be heated. On the other hand, the external electrical connections may be made at both ends of the heating unit, if this arrangement is desired. Thus, for example, one lead may be connected with the terminal 12, while the other 45 lead may be connected with the left-hand end of the resistance element through the screw 13 and washer 14.

45 In making the finished heating unit shown in Fig. 4, the helical resistance element 10 is connected with the screw 13 which will have been 50 previously inserted through its aperture 15 in the washer 14. It will be understood that the diameter of the helix is slightly less than the diameter of the screw 13 at the roots of the thread so

that the helix is expanded somewhat when it is turned on. The resistance conductor contracts by reason of its resiliency on the threaded portion of the screw thereby making a good electrical connection with the screw.

Then the resistance element is threaded through the tubular member 11, and then the tubular member with the resistance element assembled with it is inserted into the sheath 16.

- 10 The washer 14 is received in a recess or counterbore 20 provided for it in the left-hand end of the sheath 16, as viewed in Fig. 1. As shown, the washer 14 is provided with a centrally arranged depressed portion 21 of cup shape. This portion 15 21 has an external diameter substantially equal to the internal diameter of the tubular member 11. By reason of this arrangement, the cup-shaped portion 21 functions to position the screw 13 and the left-hand end of the resistance element 10 centrally of the tubular member 11, whereas the washer itself functions to position the left-hand end of the tube 11 centrally of the enclosing casing 16.

After the tubular member has thus been positioned in the sheath 16, the right hand end of the resistance element 10 is connected with the terminal 12. As shown, the terminal 12 is provided with a threaded portion 12a upon which the resistance element is turned or screwed. It will 30 be understood that the diameter of the terminal at the roots of the threads will be somewhat larger than is the diameter of the helix so that the helix is expanded somewhat when turned on. This insures a good electrical and mechanical 35 connection between the terminal and the resistance element by the contraction of the helix on the terminal.

The terminal 12, as shown in Figs. 1, 2 and 3, is provided with a head 22. The head 22 is 40 received in a recess or counterbore 23 arranged in the right-hand end of the sheath 16. The head 22 is provided with a shoulder 22a arranged centrally thereof and which is received in the right-hand end of the tubular member. This 45 shoulder has a diameter substantially equal to the internal diameter of the tubular member 11 so that it positions the terminal member 12 and the right-hand of the resistance element 10 centrally of the tubular member 11. The head 22 50 supports the right hand end of the tubular member 11 centrally within the sheath 16.

The head 22 is provided with a plurality of sector shaped apertures 24, as shown in Figs. 2 and 3, through which the insulating material 17 and 18 is inserted into the tube 11 and the sheath 16.

The assembly is now ready for loading the insulating material 17 and 18 into the sheath. The tubular member 11 and the annular space between this member and the sheath 16 is filled through the openings 24 provided in the head 22 with the powdered insulating material. To accomplish this, the sheath 16 is held in an upright position in a special vibrating machine (not 65 shown) with the end provided with the apertures 24 uppermost. As the sheath is filled with the insulating material through the openings 24, it is vibrated to shake the insulating material together and to distribute it uniformly around the 70 resistance element and within the space between the tube 11 and the sheath 16.

After the tubes 11 and 16 have been completely filled with the insulating material, a solid washer 25 is inserted in the counterbore 23 so as to cover 75 the apertures 24 provided in the head 22. Both

ends of the sheath 16 are then peened over, as shown in Fig. 3, so as to securely hold the washers 14 and the head 22.

The entire unit is now passed through a swaging or rolling machine for the purpose of compacting 5 the insulating material within the tubular member 11 and the sheath 16 to a hard dense mass, the swaging operation reducing the diameter and increasing the length of tube 11 and the sheath 16.

In case it is necessary to reduce the diameter 10 of the unit considerably, it may be desirable to pass the unit through the swaging machine a number of times so as to reduce the diameter gradually. In this event, the unit may be annealed between the successive swaging operations 15 to prevent the resistance element and likewise the tube 11 and sheath from becoming too hard and brittle.

After the unit has been swaged to the desired extent, the unit is trimmed at the right-hand 20 end so as to remove the head of the terminal 22. This may be accomplished by cutting off the ends of the tubular member 11 and the sheath 16, as indicated in Fig. 4. Preferably, the sheath 16 will be cut somewhat shorter than the tube 11 25 so that the latter will project somewhat from the sheath, as shown in Fig. 4. It is also preferable to cut the sheath 16 so that the terminal 12 will project from it somewhat, as shown. The left-hand end of the sheath will be cut away, as shown 30 in Fig. 4, so as to remove it from electrical engagement with washer 14, which as previously pointed out is in electrical engagement with the resistance element 10 and functions to connect this element with the tube 11. 35

The electrical heating unit made in accordance with this invention has a very compact and rugged construction and is arranged so that the electrical connections may be made at either end of the unit. As previously pointed out, these 40 connections may be made by connecting suitable leads to the terminal 12 and to the protruding portion of the casting 11 at the right hand end; or if it is not desired to make the terminal connections at the same end they may be made at 45 opposite ends. In this case one lead will be connected with the terminal 12, while the other lead will be connected with the washer 14 at the opposite end of the unit.

While I have shown a particular embodiment of 50 my invention, it will be understood, of course, that I do not wish to be limited thereto since many modifications may be made and I, therefore, contemplate by the appended claims to cover any such modifications as fall within the true spirit 55 and scope of my invention.

What I claim as new and desire to secure by Letters Patent of the United States, is:—

1. The method of making an electric heating unit which comprises connecting a resistance element to a metallic member, mounting said resistance element in a metallic tubular member so that said metallic member bears against one end of said tubular member, inserting said tubular member in a metallic sheath of larger diameter with said metallic member engaging said metallic sheath so as to position said tubular member within said sheath, filling said tubular member and the space between said member and said metallic sheath with electrically insulating material, then compacting said insulating material to a hard dense mass and then separating said metallic sheath from said metallic member. 60 65 70 75
2. The method of making an electric heating unit which comprises connecting one end of a sin- 75

uous resistance element to a washer, inserting said resistance element into a metallic tube, positioning said washer against one end of said tube, inserting said tube and resistance element and washer assembled with it into a metallic sheath of somewhat larger diameter than said tube, securing said tubular member in spaced relation with said sheath, filling said tube and the space between said tube and said sheath with a powdered heat refractory electrically insulating material, then compacting said insulating material by reducing the diameter of said sheath and then cutting away said sheath so as to separate it from said washer which is connected with said resistance element to electrically insulate the washer from said sheath.

3. The method of making an electric heating unit which comprises connecting a screw member to one end of a helical resistance conductor, curing said screw member to a washer having a cup-shaped central portion, inserting said resistance element with said washer attached to it into a metallic tube having an internal diameter approximately equal to the diameter of said cup-shaped portion so that said cup is fitted into one end of said tube to thereby position said resistance element with reference to said tube, inserting said tube into a metallic sheath having an internal diameter approximately equal to the diameter of said washer so that said washer is received in one end of said sheath to thereby position said tube with respect to said sheath, connecting to the other end of said resistance conductor a terminal having a head portion of a diameter approximately equal to the internal diameter of said sheath and a shoulder having a diameter substantially equal to the internal diameter of said tube and further having apertures extending through said head and shoulder, assembling said terminal with said tube and sheath so that said shoulder is received in said tube and said head is received in said sheath to thereby position said resistance element in said tube and said tube within said sheath, inserting powdered heat refractory electrically insulating material through said apertures so as to fill said tube and the space between said tube and said sheath with said insulating material, and then reducing the diameter of said sheath so as to compact said insulating material to a hard dense mass.
